UNITED STATES PATENT OFFICE.

HENRY C. FINCKE, OF NEW YORK, N. Y.

DESIGN FOR A PUZZLE-BOARD.

SPECIFICATION forming part of Design No. 29,132, dated August 2, 1898.

Application filed June 26, 1898. Serial No. 684,507. Term of patent 3½ years.

To all whom it may concern:

Be it known that I, HENRY C. FINCKE, of the city of New York, borough of Brooklyn, in the county of Kings and State of New York, have invented and produced a new and original Design for a Puzzle-Board, of which the following is a full, clear, and exact specification.

Reference is to be had to the accompanying drawings, forming a part of this specification, in which similar characters of reference indicate corresponding parts in all the figures.

Figure 1 is a perspective view of a puzzle-board showing my design. Fig. 2 is a sectional side elevation of the same on the line 2 2 in Fig. 1. Fig. 3 is a like view of the same on the line 3 3 in Fig. 1, and Fig. 4 is a similar view of the same on the line 4 4 in Fig. 1.

The design consists of a box A, from the bottom B of which and adjacent to the sides of the box rise oppositely-arranged miniature

representations of mountain ranges C C', leaving an irregular channel D between them, the bottom B being formed in the channel D with 25 a depression E, and a series of depressions F is arranged in the bottom D in the front of one of the mountain ranges, and another set of depressions G appears in the bottom B at the rear end of the box, as is plainly illustrated in the drawings.

The leading feature of my design consists of a box having miniature representations of oppositely-arranged mountain ranges, leaving a channel with a depression and sets of 35 depressions in the bottom of the box outside the channel.

I claim—

The design for a puzzle-board, as herein shown and described.

HENRY C. FINCKE.
